UNITED STATES PATENT OFFICE.

CHARLES L. BUCKINGHAM, OF NEW YORK, N. Y.

REGULATOR FOR DYNAMO-ELECTRIC MACHINES.

SPECIFICATION forming part of Letters Patent No. 320,840, dated June 23, 1885.

Application filed June 9, 1884. (No model.)

To all whom it may concern:

Be it known that I, CHARLES L. BUCKINGHAM, of the city, county, and State of New York, a citizen of the United States of America, have made a new and useful Improvement in Regulators for Dynamo-Electric Machines, of which the following is a specification.

My invention relates to that class of dynamo-regulators by which the generative capacity of the machine is controlled by short-circuiting or shunting a greater or less amount of current from the field-coils of the machine.

The principal part of my invention consists, first, of a dynamo-machine, a regulator therefor for varying the strength of current in the working-circuit, a motor capable of imparting rotation in either direction for controlling the regulator, and two electro-magnets placed in the working-circuit, and adapted 15 one to control rotation in one direction and the other to control rotation in the opposite direction; second, of a dynamo-machine, a variable resistance-shunt around the field-magnets, a regulator for varying said shunt-resistance, and a motor operated or controlled 20 by the working-circuit capable of imparting rotation in either direction to said regulator.

My invention comprises a shunt around the field-coils, which includes a variable resistance, such as a pile of carbon plates, and a novel press mechanism for subjecting the carbon plates to a greater or less degree of pressure. In order that the generative capacity of the dynamo-machine may be increased upon 30 an introduction of additional resistance into the working-circuit, that the generative capacity may be decreased upon the withdrawal of resistance from the working-circuit, and that there may be no change in generative 35 capacity while the resistance and current strength of the working-circuit remains at or near the normally-required amount, I employ a constantly-reciprocating pawl-arm, which engages the ratchet-teeth of either of two 40 wheels, respectively located on opposite sides of the pawl-arm, according as the main-line current is unduly increased or weakened, and as it thereby becomes necessary to shunt more or less current from the field-coils, and which 45 engages the teeth of neither wheel when the current is near its normal strength. The two 50 wheels gear with a common train, which

serves, when the reciprocating pawl engages one wheel, to turn a screw which compresses the carbon plates, and when it engages the other wheel to turn the screw in the opposite direction and release the pressure upon the carbon pile. The two-and-fro rotation of the press-screw, to govern the strength of current generated, is controlled by two main-line relays, the armature of one of which is adjusted to rest at front contact and close a branch or local circuit, while the armature of the other relay is adjusted to rest at back contact and there close a branch or local circuit when the current upon the working circuit is at its normal strength. When, however, the current is unduly increased, that armature which is normally at back contact is attracted, thereby breaking its local branch 60 and causing an electro-magnet to so operate as to cause the reciprocating pawl to engage with that ratchet-wheel which serves to compress the carbon pile. On the other hand, if the current were to be unduly diminished 65 the relay-armature normally on front contact would be released, thereby breaking a branch circuit and causing another electro-magnet to so operate as to cause the reciprocating pawl to engage with the other ratchet-wheel and 70 release the pressure upon the pile. By this means it is obvious that there may be any desired change in strength of main-line current before an adjustment is effected—that is, if a normal strength of current is assumed to be 75 ten ampères, the current could be diminished to nine or less, or increased to eleven or more ampères, without an adjustment taking place; and it is obvious that an adjustment may be effected by such a uniform and gradual change 80 of pressure upon the carbon pile as to cause no abrupt current variation.

I will now describe my invention by reference to the accompanying drawing.

P and N are the two poles or branches of 85 the armature of the dynamo-machine. From brush N the conductor of the main circuit includes the coils of the field-magnets and thence continues by wire 20 to point 4, where it divides into two equal branches, which reunite 90 at point 9. From point 9 the main conductor includes the coils of relay electro-magnet *a* and passes to point 10, there dividing into two equal branches, which reunite at point 15, and

from the latter point the conductor includes the coils of relay electro-magnet *b* and continues on by wire 21 throughout the length of the working-circuit back to the positive pole 5 and brush *P* of the machine. The two branches of the main conductor terminating at points 4 and 9, are differentially wound upon the core of electro-magnet *m*. Branch 5 8 includes the upper coils of *m*, and is completed through 10 front stop, *d*', and armature of relay *a*. Branch 6 7 includes the lower and oppositely-wound coils of *m*. In like manner the two branches between points 10 and 15 are differentially wound upon the cores of electro-magnet *n*. Branch 11 14 includes the upper coils of *n*, and 15 is completed through back contact-point, *e*', and armature of relay electro-magnet *b*. Branch 12 13 includes the lower and oppositely-wound coils of *n*. When the relay-armatures are in 20 the positions shown in the drawing it is apparent that, however strong the main-line current, it will divide through the coils of *m* and *n* and produce no magnetic effects; and under such conditions the armature-lever *l*, pivoted at *p*', 25 may be so adjusted by means of springs *s*' and *t*' as to assume a horizontal position. The armature of relay *a* is so adjusted by its retracting-spring *x*' as, under the influence of a normal strength of current, to rest upon its 30 front contact, *d*', and close the branch conductor 5 8; but, in the event of any considerable decrease of current, the armature of *a* will be released and retracted to its back contact, *e*', thereby breaking branch 5 8, and leaving 35 *m* subject to the single branch 6 7. The armature of *b* is so adjusted by its retracting-spring *y*' that a normal current will not cause its attraction, and under that condition it will rest on back contact; but an abnormally strong 40 current will cause its armature to be attracted to front stop, *f*', thereby breaking branch 11 14 and leaving *n* under the influence of branch 12 13. It is obvious that if ten amperes be considered a normal current, springs *x*' and *y*' 45 may be so adjusted that the armature of *a* will not be retracted from its stop until the current has been diminished to nine or less than nine ampères, or that the armature of *b* will not be attracted from its front stop until the 50 current has increased to a strength of eleven ampères or more; or spring *x*' *y*' may be so adjusted that the slightest variation of current strength above or below a normal amount will cause one armature to be attracted or the other 55 retracted. Upon a decrease of main-line current, and a retraction of the armature of *a*, electro-magnet *m* is attracted and slotted arm *y* is thrown to the left. On the other hand, upon the attraction of armature of relay *b*, the armature of *n* is attracted and *y* is moved to the 60 right. From point 2 and brush *N* a shunt-wire, *h*', connects with the insulated base-plate *k* of the carbon resistance-pile *R*; and from the cap-plate *j* of the pile a wire, *k*', connects with the main conductor at point 1. The 65 current from brush *N* may reach point 1 of the

main conductor by two paths—one through the field-coils and the other through carbon pile.

An increase or decrease of pressure is applied to the carbon pile by the following 70 agency: Rotation is imparted to the driving-pulley *p* by a belt, *D*, and upon the same shaft with *p* is a small pulley, *o*, which is connected by a belt-gear with wheel *q*, fixed to a shaft which carries a crank or eccentric, *r*, to which is attached a link-arm, *s*. *u* is a rock-shaft, and at one end its arm *t* is connected to *s*, while at its other end its arm *v* is jointed to a reciprocating double pawl-arm, *x*. Arm *x*, at its lower end, has a pin which plays in a slot in the vertical arm *y*. Arm *x* also slides between two leaf-springs, which, when arm *y* is in a central position, cause arm *x* to reciprocate continuously in a middle position without engaging the teeth of either wheel *W* or *Z*. When double armature-lever *l* is attracted by either *m* or *n*, arm *y* presses *x* to one side or the other, and causes the reciprocating movement of *x* to be communicated to wheels *w* and *z*, thus giving them a step-by-step movement. If the main-line current is too strong, arm *x* is thrown into engagement with wheel *z*, and through gear-train *d e f g* the shaft *h*, having a male screw, is turned into the female screw *i*', so as to give *i*' a longitudinal downward movement to compress the carbon pile and lower the resistance of the shunt around the field-coils. On the contrary, when the main-line current is too weak and pawl-arm *x* engages with *w*, shaft *h* is turned in an opposite direction, and the 95 pressure from the resistance-pile is removed. As here shown, pawl-arm *x* will be held closely against wheels *W Z*, when armature *l* is tilted to one side or the other and upon each backward movement of the reciprocating pawl to 100 engage a successive tooth, arm *l* will be vibrated. In order that *l* may be comparatively free to vibrate, its armatures must never come in magnetic contact with the cores of *m n*. These cores must be faced with non-magnetic 105 material, or there must be limiting-stops provided.

Instead of differential magnets *m n* ordinary local electro-magnets may be used whose local circuits may both be normally held open 115 or both normally be held closed by relays *a b*. It is also apparent that a great variety of motors may be employed to communicate rotation from the shaft of the dynamo to the screw-shaft *h* of the resistance-pile. It will be seen 120 that with the same magnet system *a b*, instead of a reciprocating pawl a constantly-rotating wheel could be employed which would be carried into gear with wheel *W* or *Z*, as occasion required, to effect a to-and-fro rotation. It is 125 also obvious that an electro-magnetic motor may be used to rotate screw-shaft *h* in one direction or the other by directing current to said motor by means of relay-magnets *a b* and proper branch or local circuits.

I am aware that an electro-magnet placed 130 in the working-circuit for controlling the to-

and-fro rotation of a motor which acts to vary the resistance of a shunt around the field-magnets of a generator is not new.

What I claim, and desire to secure by Letters Patent, is—

1. The combination of a normally inactive motor capable of rotation in both directions to vary the electro-motive force of a dynamo-electric machine, two main-line electro-magnets, one of whose armature-levers normally rests upon a front stop and the other upon a back stop, and electrical contacts, one of which is broken by one electro-magnet upon an increase of main-line current to cause 10 rotation of said motor in one direction, and the other of which is broken by a decrease of main-line current to cause said motor to rotate in the opposite direction.

2. The combination of a dynamo-machine, 20 a shunt-branch around the field-coils of said dynamo-machine, a variable resistance in said shunt, a motor capable of remaining inactive and of effecting rotation in either direction for controlling said shunt-resistance, and two electro-magnets, one of which is responsive to an increase and the other to a decrease of current, placed in the working-circuit for controlling the operation of said motor.

3. The combination of a normally inactive 30 motor capable of effecting rotation in either direction, a dynamo-machine regulator controlled by said motor for varying the current strength of the working circuit, two main-line electro-magnets, one of which is responsive to an increase and the other to a decrease of current, for controlling the operation of said motor, and a dynamo-electric machine.

4. The combination of a working-circuit, 40 two electro-magnets in said circuit respectively responsive to an increase and decrease of current above or below a normal strength, whose armatures are so adjusted that normally one rests on a front stop and the other on a back stop, and a motor whose rotation in one direction is controlled by one of said electro-magnets, while the rotation of said motor in the opposite direction is controlled by the second of said electro-magnets.

5. The combination of a main line, two relay-

magnets whose armatures are so adjusted that 50 normally one rests on a front stop and the other on a back stop, and a gear-train and a motor which communicates rotation in one direction upon the attraction of that relay-armature which normally rests on its back stop, 55 and which communicates rotation in an opposite direction upon the retraction of that relay-armature which normally rests upon its front stop.

6. The combination of a dynamo-machine, 60 a shunt-branch around the field-coils of the machine, a carbon pile in said shunt, a screw-press for varying the resistance of said shunt, a motor for rotating the screw of said press in a to-and-fro direction, and two relay-magnets 65 whose armatures are adjusted, as described, to direct the rotary action of said motor in one direction or the other.

7. In a dynamo-machine regulator, the combination of relay electro-magnets *a b*, whose 70 armatures are adjusted as described, local branches which are normally closed by said relay-armatures, one at front and the other at back contact, differential electro-magnets *m n*, armature-lever *l*, double pawl-arm *x*, geared 75 with the shaft of the dynamo-machine, gear-trains *w c e f g* and *z d e f g*, or their equivalents, screws *h i*, and carbon pile *R*.

8. In a dynamo-machine regulator, the combination of relay electro-magnets *a b*, whose 80 armatures effect electrical contact, one at a front and the other at a back stop, two electro-magnets respectively controlled by said relay electro-magnets, armature-bar *l*, arm *y*, and double pawl-arm *x*, and ratchet-wheels *w z*.

9. In a dynamo-machine regulator, the combination of two differential electro-magnets, *m n*, whose differential coils are normally closed, and two relay electro-magnets, *a b*, for 90 opening and closing branches embracing coils of said differential electro-magnets, substantially as described.

Signed by me this 31st day of May, 1884.
CHARLES L. BUCKINGHAM.
